UNITED STATES PATENT OFFICE.

CLIFFORD OLDER, WALTER SCOTT GEARHART, AND HARRY EDMUND BILGER.
OF SPRINGFIELD, ILLINOIS.

AUTOMATIC LAMP-EXTINGUISHER.

No. 907,089.

Specification of Letters Patent. Patented Dec. 15, 1908.

Application filed July 28, 1908. Serial No. 445,709.

To all whom it may concern:

Be it known that we, CLIFFORD OLDER, 5 WALTER SCOTT GEARHART, and HARRY EDMUND BILGER, citizens of the United States, residing at Springfield, in the county of Sangamon and State of Illinois, have jointly invented a new and Improved Automatic Lamp-Extinguisher, of which the following is a full, clear, and exact description:

10 Our invention relates to automatic lamp extinguishers, our more particular purpose being to provide an approved construction containing a wick snuffer co-acting in connection with a weight, to extinguish the 15 flame whenever the lamp is thrown over upon its side or is inclined beyond certain limits in any direction.

More particularly stated, our invention 20 comprises mechanism for rendering the extinction of the flame as nearly positive as practicable, in order to reduce the possibility of a conflagration in case of the accidental overturning of the lamp.

Reference is to be had to the accompanying 25 drawings forming a part of this specification, in which similar characters of reference indicate corresponding parts in all the figures.

Figure 1 is a central vertical section on 30 the line 1—1 of Fig. 2, looking in the direction of the arrow, through a lamp burner provided with our improvement, this view showing a spherical weight resting in a receptacle having a conical bottom so as to 35 keep the weight normally centered, and a disk resting on the weight and connected by a fork with a pair of snuffers and adapted to actuate the same for the purpose of extinguishing the flame whenever the weight 40 is displaced beyond a certain limit; Fig. 2 is a horizontal section upon the line 2—2 of Fig. 1, looking in the direction of the arrow, and showing the wick, the burner tube, the snuffers and the fork for actuating the 45 snuffers; Fig. 3 is an enlarged fragmentary side elevation showing the manner in which the snuffers are pivotally mounted upon the upper end of the burner tube; Fig. 4 is an enlarged fragmentary section showing the 50 snuffers as closed above the wick for the purpose of extinguishing the flame of the latter; and Fig. 5 is a view partly in section and partly in elevation, showing the snuffers as closed as in Fig. 4, the view being otherwise similar to Fig. 3.

At 6 is shown a burner casing which is provided with air holes 7. A burner tube appears at 8, and extending partially into it is a star wheel 9 mounted upon a revoluble stub shaft 10 in order to enable it to be 60 turned by hand. The star wheel 9 engages the wick 11 and is adapted to raise and lower the same relatively to the burner tube in the manner heretofore understood in this art.

At 12 is a burner screen consisting of a 65 perforated plate disposed horizontally and reaching entirely across the burner casing.

A pair of snuffers 13, 14, each having substantially the form of a sector-shaped hood, are pivotally mounted upon pins 15, the latter being secured rigidly upon opposite sides of the burner tube 8. The sectors 13, 14 are provided with slots 16 into which extend tines 17 of a fork 18. The arrangement is such (see Fig. 3) that when the fork 75 18 is raised or lowered, the hoods 13, 14 are rocked upon the pins 15. The hoods 13, 14 are provided with bearings 13^a, 14^a integral with them. The hood 13 is further provided with a bead 13^b (see Fig. 4) adapted to 80 slightly overlap the adjacent edge of the hood 14.

The burner casing 6 is provided with a cap 19 having an aperture 19^a from which the flame issues while the lamp is burning. 85 Mounted partially within the burner casing 6 and secured rigidly upon the burner tube 8 is a cup 20 provided with a conical bottom 21. A spherical weight 22 is free to move in the cup 20. Mounted rigidly upon the fork 18 90 is a disk 23 of slightly smaller diameter than the cup 20. This disk normally rests upon the weight 22 and is adapted to slide vertically in relation to the cup. When the weight 22 moves in a direction lateral to the general 95 vertical axis of the cup 20, the disk 23 is moved upward by the displacement of the weight 22. This is because of the inclination of the bottom 21, owing to its conical form. The cup 20 is provided with a cover 100 24, through which the fork 18 extends, this fork being guided by the disk 23, the cover 24 and the burner screen 12, through which it extends.

When the parts are in normal position, as 105 indicated in Figs. 2 and 3, the ball 22 occupies its lowermost position on the conical bottom 21. If, however, the lamp be accidentally thrown down or turned in such a direction that the burner tube 8 is inclined 110

beyond a certain limit, the weight 22, being displaced from its normal position and tending to follow the inclination of the conical bottom 21, moves slightly in a lateral direction relatively to the burner tube 8, the result being that the fork 18 is pushed slightly toward the upper end of the burner tube. This movement causes the hoods to rock upon the pivots 15 and to assume the position indicated in Figs. 4 and 5, thereby extinguishing any flame there may be issuing from the upper end of the wick 11.

It will be noted that whenever the lamp is righted, that is to say, moved into its normal position, as indicated in Fig. 1, the weight 22 rolls into the middle of the conical bottom 21, thus restoring all parts controllable by the weight to their respective normal positions.

Having thus described our invention, we claim as new and desire to secure by Letters Patent:

The combination with a burner, of a pair of snuffers movable toward and from each other, for the purpose of extinguishing a flame associated with said burner, a cup provided with a conical bottom in connection with the burner, a weight disposed within the cup and resting upon the bottom, a disk above the weight and movable in the cup, and a connection between the disk and the snuffers for actuating the same when the weight is moved. 25 30

In testimony whereof we have signed our names to this specification in the presence of two subscribing witnesses.

CLIFFORD OLDER.

WALTER SCOTT GEARHART.

HARRY EDMUND BILGER.
